ELEVATOR CONTROL SYSTEM

Filed Nov. 19, 1927

UNITED STATES PATENT OFFICE

MILTON BARUCH, OF BEVERLY HILLS, CALIFORNIA, ASSIGNOR TO WESTINGHOUSE ELECTRIC & MANUFACTURING COMPANY, A CORPORATION OF PENNSYLVANIA

ELEVATOR CONTROL SYSTEM

Application filed November 19, 1927. Serial No. 234,409.

My invention relates to control systems for motor-driven machines and has special reference to control systems for elevators, hoists and similar machinery.

- 5 An object of my invention is to provide a control system of the type designed for intermittent service wherein the electrical driving device will be at rest when no service is desired.
- 10 Another object of my invention is to provide a control system of the Ward-Leonard type where the driving motor-generator set will be automatically stopped when the working motor is not in substantially continuous service.

Another object of my invention is to provide a control system of the Ward-Leonard type wherein the driving motor-generator set will be shut down whenever a predetermined time elapses between successive operations of the driven machine.

Another object of my invention is to provide an elevator-control system having a Ward-Leonard drive and having means for stopping the motor-generator set whenever a predetermined time elapses by the successive calls for the services of the elevator.

My invention will be described with reference to the accompanying drawing where- 30 in the sole figure is a diagrammatic view of my control system as applied to a push-button-controlled elevator to be operated between the limits of four floors.

Referring to the drawing, I have illustrated an elevator car C suspended upon a cable Ca which passes over a hoisting drum D to a suitable counterweight Cw. The hoisting drum D is directly coupled to the armature EM' of a "working" elevator motor EM. A motor-generator set, comprising a generator G, preferably of the compound-wound type, having its armature G' and its series field windings GSF continuously connected to the terminals of the elevator motor armature EM', and squirrel-cage alternating-current motor M having its rotor M' directly coupled to the generator armature G' by means of a shaft S.

The driving motor M is illustrated as being of the three-phase type having its

stator windings MS connected to the three-phase conductors of a suitable source of alternating-current supply designated, as I, II, and III.

A direct-current Exciter E having its armature E' coupled to the shaft S and having its field winding EF connected in shunt relation to the armature E', is designed to supply the necessary direct current for exciting the field windings of the elevator motor EM and the generator G, respectively, and also to supply the necessary operating current for certain of the controlling relays, as will hereinafter be described.

The field winding EMF of the elevator motor EM is illustrated as being permanently connected across the terminal conductors L1 and L2 which lead from the exciter E. Thus, the direction of movement of the motor EM is controlled by the selective excitation of a separately excited field winding GF, provided for the generator G, to be selectively connected to the exciter conductors L1 and L2 having current traversing the winding in opposite directions through the operation of up and down-direction switches 1 and 2.

A series of push-buttons F1, F2, F3 and F4 are illustrated as being mounted at suitable locations on the first, second, third and fourth floors, respectively, to be operated by persons desiring to use the elevator. The function of the push buttons is to operate the controlling switches for calling the car to the respective floors corresponding to such buttons.

Similar push-buttons C1, C2, C3 and C4 are mounted upon the elevator car C to be operated by passengers within the car to cause the elevator to travel to the desired destination.

Suitable floor-selecting devices, illustrated as switches 1SD, 2SD, 3SD, 2SU, 3SU and 4SU are so mounted in any suitable manner as to be operated in accordance with the movements of the elevator car C as it travels up and down in its hatchway. The switches may be of any suitable two-position type having the characteristic of remaining in

either position until moved, through some outside agency, to the opposite position.

I have illustrated suitable doors D1, D2, D3 and D4 as representing the usual closures for the openings in the hatchway for the first, second, third and fourth floors, respectively. The doors may be provided with suitable locking devices (not shown) and may have mounted thereon the usual door switches, designated as 10, 11, 12 and 13, to be normally in a closed-circuit position but operable to an open-circuit position through the agency of a retiring cam RC carried by the elevator car C, when the car is adjacent to the door.

The driving motor M of the motor-generator set is suitably controlled, through the operation of relays MG, AM and T, for connecting the three-phase windings of the motor stator MS to the phase conductors of the AC supply upon suitable operation of these relays.

The relay T is provided with a dash-pot so disposed as to permit a rapid movement of the armature 15 of this relay when drawn upwardly but to retard the downward movement of the armature for a predetermined adjustable length of time.

The operation of my system will best be understood when described with reference to an assumed elevator operation.

Assuming that the elevator is standing at the fourth or uppermost floor and that all of the relays are in their illustrated positions and assuming that a person at the third floor, desiring to use the elevator car C, operates the button F3. The operation of the button F3 completes a circuit for energizing the down-direction-determining relay DR and the cam-retiring magnet 27, which extends from the line conductor II of the AC supply, through conductors 16 and 17, contact members *a* of a relay AL, conductors 18 and 19, the contact members of the push button F3, conductors 20 and 21, the coil of floor relay FR3, conductor 21, the floor-selector switch 3SD (now in closed position, since the car is above the third floor), conductors 22 and 23, the coil of down-direction-determining relay DR, conductor 24, contact members *a* of up-direction-determining relay UR, conductors 25 and 26, the coil 27 for the retiring cam RC and conductors 28 and 29, to line conductor I of the AC supply. The energization of the coil 27 for the retiring cam RC moves the cam out of engagement with the door switch 13, permitting this switch to close, while the energization of the down-direction-determining relay DR completes a circuit for operating the down-direction switch 2 which will be hereinafter more fully described.

Upon the closing of the door switch 13, a circuit is completed for energizing door

relay AL which extends from line conductor II, through conductors 16 and 17, the coil of the door relay AL, conductor 30, door switches 13, 12, 11 and 10, in series relation, conductors 31 and 32, gate contact members 34 (such as are usually disposed to be closed by the car gate structure 35, a portion of which only is illustrated) and conductor 29, to line conductor 1.

The operation of the relay AL causes the motor-generator set to be started to condition the generator G to supply the necessary operating current to the elevator motor EM. This effect is accomplished through the energization of the timed relay T, energized through contact members *c* of relay AL, the circuit for which extends from line conductor II, through conductor 16, contact members *c* of relay AL, conductor 33, the coil of timed relay T and conductor 34, to line conductor I. The energization of relay T raises the armature 15, permitting switch 35 to assume its closed-circuit position.

Switch 35 completes a circuit for relay MG which extends from line conductor I, through conductor 36, coil of relay MG, conductor 37, switch 35 and conductor 38, to line conductor II. Relay MG completes the circuit for the motor-controlling relay AM, as hereinafter described.

It will be noted that one of the phase windings 40 of the motor stator MS is permanently connected to line conductor I through resistor 41 and conductor 42. Thus, the closing of contact members *a* and *b* of relay AM connects the remaining phase windings 43 and 44 to the remaining phase conductors II and III by way of circuits which extend from line conductor II, through conductor 45, contact members *a* of relay AM, conductor 46, resistors 47, conductor 48, winding 43, to the star point 49; and from line conductor III, through conductor 50, contact members *b* of relay AM, conductor 51, resistor 52, conductor 53, and winding 44, to star point 49. The motor M is thus started to drive the generator armature G' and the exciter armature E'.

A relay is provided for each phase of the stator winding MS to shunt the resistors 41, 47 and 52 from the motor stator circuits, these relays being designated, respectively, as R1, R2 and R3. The coils for the relays R1, R2 and R3 are connected in series relation with each other and are supplied with current from the exciter E.

By suitable selection of the coils for the relays R1, R2 and R3, these relays may be caused to operate at any predetermined speed of the motor M, since the operating current for these coils depends upon the building up of voltage in the exciter E. When the voltage of the exciter E reaches a predetermined value, the relays R1, R2 and R3 will be operated to close their contact

member and thereby connect the windings of the stator MS directly to the supply conductors I, II and III.

As the exciter builds up voltage, direction switch 2 will be energized through the contact members *b* of down-direction-determining relay DR by way of a circuit which extends from exciter line conductor L1, through conductors 55 and 56, contact member *b* of relay DR, conductor 57, the coil of down-direction switch 2, conductor 58, contact members *d*, of relay AL (now in closed-circuit position) and conductor 59, to the exciter line conductor L2. The operation of down-direction switch 2 will cause excitation of the generator-separately-excited field winding GF in the usual manner through a circuit which extends from line conductor L1, through conductor 60, contact members *b* of down-direction switch 2, conductors 61 and 62, field-winding GF, conductors 63 and 64, contact members *a* of down-direction switch 2 and conductor 65, to line conductor L2.

Since the field winding EMF for the elevator winding EM is permanently connected across the exciter line conductors L1 and L2, through conductors 61 and 62, the excitation of the generator-field-winding GF and the consequent supplying of voltage to the armature EM' of the elevator motor, the motor EM will be caused to start to thereby move the car downwardly.

It will be noted that the circuit for energizing the floor relay F3 traced through normally closed contact members *a* of relay AL and the push-button F3 was transferred through the operation of relay AL from contact members *a* to contact members *b* of this relay and, by reason of a self-holding circuit for the relay FR3, this relay was maintained in operative position until the switch 3SD was opened. This holding circuit extends from line conductor II through conductors 16 and 17, contact members *b* of relay AL, conductors 64 and 65, contact members of relay FR3, conductor 21 and thence through the coil of relay FR3 as previously described.

As the car arrives adjacent to the third floor, a finger SD, carried by the car, will engage the selector switch 3SD and move the same to open-circuit position, deenergizing the down-direction-determining relay DR, the down-direction switch 2 and floor relay FR3.

The opening of switch 3SD also opens the circuit to the coil 27 for the retiring cam RC and, since the car C is now adjacent to the third floor, the cam RC will operate to open the door switch 12 associated with the door D3 for the third floor. The opening of the door switch 12 breaks the circuit for the relay AL, permitting this relay to drop out and thereby open the circuit to the timed

relay T. The timed relay T, however, does not immediately open the switch 35 to stop the driving motor-generator set by reason of the action of the dash-pot 6 which permits the armature 15 to descend very slowly under the influence of the spring 66.

The time allowed by the dash-pot 6 is preferably adjustable to fit the running losses and the starting losses of the motor-generator set to which it is applied. That is, the time should be slightly in excess of the time during which the losses of the set, when running idle, causes a consumption of current equal to that due to the losses caused by starting the set one time. However, this time may be extended to fit the conditions of any particular installation and may depend upon other factors such as the estimated frequency of calls for service, thus varying the time through a wide range, from two to forty seconds, or more.

Assuming that the time allowed by the dash-pot 6 for the opening of switch 35 is 20 seconds, during which time the person who desired to use the car at the third floor opens the door D3 and enters the car C. Assuming that this person desires to travel to the first floor and, therefore, operates the button C1 within the car C, a circuit will be completed for energizing floor relay FR1 which circuit extends from line conductor II, through conductors 16, 17, 18 and 67, contact members of the push-button C1, conductor 68, the coil of floor relay FR1, switch 1SD (now in closed position) and conductor 23 and thence through the coil of relay DR and the coil 27 of the retiring cam RC as previously described for these coils. The subsequent starting of the elevator, through the operation of the relay AL and direction switch 2, will be performed in the same manner as that previously described.

The operation of the elevator in the upward direction is similar, in all respects, to the operation described for the down-direction with the exception that, in such case, relay UR and up-direction switch 1 will function through selector switches 2SU, 3SU or 4SU, respectively, instead of relay DR, down-direction switch 2, etc., as previously described.

Assuming, for example, that, after the passenger who boarded the elevator at the third floor, leaves the car at the first floor and no call buttons F1, F2, etc., are operated until the lapse of the time allowed by the dash-pot 6 of the timed relay T, this relay being deenergized by the opening of the door switches 10, 11, 12 or 13 occasioned by the release of the retiring cam RC when the car stops at the respective floors, will open the switch 35 to deenergize relay MG and AM to stop the motor M. However, assume, thereafter, that one of the buttons F1, F2, etc., or C1, C2, etc., is operated, the

motor M will be instantly started to condition the elevator to answer such call for service.

Thus far, the starting of the motor-generator set has been described as caused by the operation of a floor-landing push-button F1, or push-button F2, etc. Under these conditions there is a slight delay in the starting of the generator G on account of the time required for the motor M to accelerate to its normal speed. When a call for service is made from one of the landing buttons, such slight delay does not necessarily inconvenience the prospective passenger, since he is not made aware of unusual delay. However, if the car C is standing at a floor at which a person desires to board the car and the motor M is at rest, such person upon entering the car and operating the button C1, C2, etc., for the floor to which he desires to travel, will experience the delay necessary for the motor M to come up to speed. Such delays impress themselves upon the mind of the person using the elevator since he is ready to travel but the elevator is not and, in order to avoid this unpleasant psychological condition, I have provided a relay BA, the coil of which is in circuit with the contact members 34, to be energized at all times when the car gate is closed.

When the prospective passenger opens the gate preparatory to entering the car C, relay BA will be deenergized and will close its contact members, thus energizing relay T to cause starting of the motor M.

Hence, the motor M will have such time as elapses between the opening of the gate and the subsequent operation of the car button C1, etc., to accelerate it to its normal working speed. The circuit for the timed relay T, closed by deenergization of relay BA, extends from line conductor II, through conductors 69, 70, 71 and 33, the coil of relay T and conductor 34, to line conductor I.

It will thus be seen that I have provided a control system for an elevator using the Ward-Leonard drive wherein the generator driving motor will be stopped during substantially all such times as no calls for service exist and wherein the first registered call for service, after such stopping of the motor-generator set, starts the set to permit the normal operation of the elevator thereafter. When the elevator is used only infrequently, this method of controlling the motor-generator set results in the saving of such current as would be required to drive the motor-generator set when idle. The advantage of this is particularly apparent when it is noted that the idling losses of a large alternating current motor, such as is required to drive the generator in an installation of the type illustrated, if extended over a long period of time, may

consume a quantity of current which performs no valuable work and it is objectionable to have this set operating over long periods of time during which the elevator hoisting motor is idle.

The form of the invention described above is merely illustrative and I do not desire to be limited to any of the details shown except insofar as they may be defined in the appended claims.

I claim as my invention:

1. In an elevator-controlling system, an elevator operable past a plurality of floors, motive means therefor, a motor-generator set for supplying energy to said motive means, call means for actuating said motive means to cause said elevator to travel to any of said floors and to stop thereat, a closure for said elevator permitting entry to said elevator, and means, operable in response to actuation of any of said call means or to the opening of said closure for starting said motor-generator set and operably responsive to the lapse of a predetermined time after the stopping of said elevator for stopping said motor-generator set.

2. In a controlling-system for an elevator operable past a plurality of floors, motive means for said elevator, a motor-generator set for supplying energy to said motive means, a closure for said elevator, and means operable by opening said closure for starting said motor-generator set and operable by the stopping of said elevator for stopping said motor-generator set upon the lapse of a predetermined time thereafter.

In testimony whereof, I have hereunto subscribed my name this tenth day of November, 1927.

MILTON BARUCH.
